STUDIO COUCH

Hugo Perlesz, Chicago, Ill., assignor to Burton-Dixie Corporation, Chicago, Ill., a corporation of Delaware

Application August 15, 1932, Serial No. 628,874

4 Claims. (Cl. 5—18)

This invention relates to beds, and has been illustrated as embodied in expandible beds of the studio couch type. Although some of the features of this invention may be used without the others, the embodiments which have been chosen for illustration and description show various of the novel features in combination. In these embodiments the beds comprise two separable portions which are normally secured together by equalizer bars. These equalizer bars have the dual function of maintaining the parts in parallel relationship and of making the movable part run true with respect to the stationary part.

Among the numerous objects accomplished by this invention, is the provision of a couch which may be economically constructed and which though expandible will have the appearance of the ordinary couch; and the provision of an expandible bed which may be either expanded or entirely separated with the utmost ease; also the provision of an expandible bed structure in which the spring fabrics are only slightly separated vertically without loss of strength as compared with ordinary expandible beds.

With these and various other objects in view, the invention may consist of certain novel features of construction and operation, as will be more fully described and particularly pointed out in the specification, drawings and claims appended hereto.

In the drawings, which illustrate an embodiment of the device, and wherein like reference characters are used to designate like parts,

Figure 1 is a perspective view of either form of the invention in its contracted position;

Figure 2 is a similar view of the preferred embodiment of the invention in its extended unitary position.

Figures 3 and 4 together comprise an end view of the structure of Figure 2 with the sections separated;

Figure 5 is a fragmentary horizontal sectional view taken below the spring fabric of the structure of Figure 2;

Figure 6 is a sectional view showing the end of the trundle section of Figure 1 in its contracted position;

Figure 7 is a fragmentary sectional view taken on the line 7—7 of Figure 5;

Figure 8 is a fragmentary detail view of the latch features;

Figure 9 is a view similar to Figure 5 but illustrating a modified form in its contracted position;

Figure 10 is a fragmentary sectional view taken along the line 10—10 of Figure 9;

Figure 11 is a fragmentary sectional view taken along the line 11—11 of Figure 9; and

Figure 12 is a fragmentary perspective view of a slight modification of the structure of Figures 9 to 11.

Although my invention may take various forms, only two, with a slight modification have been chosen for illustration, the preferred form being shown in Figures 1 to 8. Each form in its normal or contracted position includes the cushion or mattress 2 supported on a suitable bed spring and frame which is preferably hidden from view by the upholstery 4. Underneath the cushion 2 is a second mattress 6 which is supported directly on the spring fabric 8, which latter is carried by the main frame 10 in the usual manner, except for features to be described. Arranged under the spring fabric 8 is the trundle frame 12 which is provided with the spring fabric 14, and is mounted on the trundle box 16. The trundle box is supported by rollers 18 to permit its free movement from its contracted position to its extended position.

In the preferred form shown in Figures 1 to 8, the main frame 10 is provided with a side bar 20 along its back side, as shown best in Figures 5 and 7. In order to insure the uniform and easy movement of the trundle box 16 and the trundle frame 12, equalizer bars 22 are provided, as best shown in Figure 5. These two bars are pivoted to each other by a pivot 23.

One of them is pivoted at one end by the pivot 24 to the side bar 20, while the other one is pivoted at its corresponding end by the pivot 25, to a coupler bar 26 normally secured to trundle frame 12. Each of

the bars is pivoted at its opposite end by the sliding pins 27, each of which slides in a slot 28, one of which is formed in the side bar 20 and the other of which is formed in coupler bar 26.

To permit the two balance rods 22 to completely collapse under the side bar 20, one of them may be provided with a stirrup portion 29 to fit around the other one. This stirrup portion is desirable because of the fact that, as shown in Figures 5 and 7, the righthand end of one bar 22 is pivoted to coupler bar 26 below it, and the other end of the same bar is pivoted to side bar 20 above it.

The other bar is just the reverse, so it is clear that it is necessary for them to cross one another vertically in some manner. With this construction it is clear that the trundle frame must remain in parallel relationship with the main frame, so that

it is impossible for it to become twisted and move irregularly. The equalizer bars also cause the trundle bed to run true, i. e., laterally centered

45

50

55

40

55

as well as parallel, so that it cannot rub against the main section.

As the trundle box and frame are drawn out, the outward movement is normally limited by the 5 coupler bar 26, as shown best in Figure 5, where it is seen that the ends 30 of the bar 26 contact front legs 31 of main frame 10. When in this position, it is desirable that the contents of the trundle box be readily accessible. For this purpose, of course, a drawer could be provided to be drawn out further, but under some conditions there would not be room for this further extension. It is therefore preferred that the spring frame be hinged.

15 The hinging of the spring frame is shown best in Figure 4, in which it is seen that the frame 12 is pivoted to stub legs 32 by suitable pivots 34. As shown in dotted lines, this pivotal point is located sufficiently far forward when the legs are 20 fully extended but not separated, to prevent interference with the main bed portion or its mattress, and at the same time is as far back as practicable so as to permit the ready removal of the contents of the trundle box.

25 To assist in raising the frame 12 and to hold it steady in either the upper or lower position, the system of levers and springs best shown in Figure 4 is provided, preferably at each end of the trundle box. Pivoted by pivot 35 near the front 30 side of the trundle box is a toggle lever 36 to which by means of pin 37 is pivoted the toggle lever 38 which at its other end is pivoted to the hinged frame 12 by the pivot 39. A suitable spring 43 is attached to the trundle box at the 35 pivot 39 and to the end of lever 36 at the point 45 beyond the pivot 37, as shown. As clearly seen from a comparison of Figures 4 and 6, the spring 43 is drawn out by the lowering of the hinged frame 12. Also, the effect of the spring is much 40 stronger relatively when the frame is up than when it is down, due to two causes: first, the frame in its upper nearly vertical position is more nearly balanced in itself than when extending horizontally; and second, the levers 36 and 38 are 45 more nearly in a straight line, so that a force exerted on them by the hinged frame 12 has a smaller component in the spring expanding direction. Through the combination of these variable features, and through the use of a proper 50 spring, the frame 12 may be made to stay in either position, and at the same time be nearly enough balanced in all positions so that its operation will not be difficult. Also through this 55 combination of variable features, and due to the fact that the spring is in its most effective position with respect to the levers when the frame is about halfway up, there is a tendency for the spring frame 12 to raise itself as soon as it has been well started. The downward movement of 60 the hinged frame 12 is limited by the shoulders 48 of legs 49 secured to said frame, and arranged to rest on the bracket 50 forming a continuation of lever 36.

65 The trundle frame 12 and box 16 are secured to the coupler bar 26 by means of brackets 56 attached, as by welding, to the stub legs 32. The brackets 56 are shaped, as clearly shown in Figures 4 and 8, with downwardly turned ends or tongues, notched as at 58, and provided with wide 70 downwardly facing shoulders 60. These tongues are in suitable positions to receive the coupler bar 26, being relatively inserted into holes 62 therein. These parts are in such positions as to be readily accessible when the bed is expanded, as shown in 75 Figure 2. Secured to the under side of coupler

bar 26 is a spring latch 64 punched to engage notches 58 when bar 26 is raised onto the tongues of brackets 56. The coupler bar 26 can be released from the tongues simply by pressing on handles 66 of latches 64. When thus released bar 26 will drop into pocket 68 of end bar 70, where it will remain in a convenient position for subsequent attachment. When the trundle box and frame are in their normal position it is desirable that they be movable with the main bed 10 frame, and so connected therewith that when the main frame is lifted it will lift the trundle box and frame also. This result may be very readily secured by providing a hole 74 in each of the front 15 legs of the main frame and positioned to receive tongues 75 forming extensions of brackets 50. The tongues 75 do not ordinarily contact with these legs, and therefore, there is no friction to contend with. However, when it is desired to lift the bed, the front side of the trundle box will be 20 suspended by the means discussed. The tongues 75 are preferably notched as shown to lock the bed in its contracted position during moving. The rear side of the trundle section will be supported by the end bars 70 through the coupler 25 bar 26 and brackets 56. Shoulder 60 of bracket 56 will rest on coupler bar 26, the ends 30 of which will rest on end bars 70.

Although the upholstery may take many forms, the preferred form is illustrated in Figures 1, 2 30 and 6, in which it is seen that the front, side and ends of the bed are covered with upholstered panels while the main section of the bed is provided with a cover secured thereto by nailing strips in close proximity to said panels. The 35 mattresses may be of any type, or may be of different types, and that on the main section may be conveniently built onto the frame. Of course, if it should be desired to revise the couch so that the upper section slides off of the lower 40 section, the upholstery and other details would be changed accordingly.

From the foregoing, and from the drawings, it may be seen that this bed in its normal condition may be used as any other bed of the draw-up type, the trundle section being hidden from view during the daytime. At night it may be drawn out with the utmost ease due to the particular use of the equalizer bars, as shown. The coupler bar 26 acts as a stop for the trundle section when this section reaches the proper position for coacting with the main section to form one double bed. However, if it is desired to use the two sections as twin beds, it is merely necessary to press the handles 66 of the spring 50 latches 64 and allow the coupler bar 26 to drop off of the bracket 56. The trundle section is then entirely disconnected from the main section, and may be moved around at will. When it is desired to reconnect the beds, it is merely necessary to move the trundle section back to the position of its release and to raise the coupler bar 26 onto the tongues of brackets 56 where it is held by the latches 64. During the 55 period of separation, the coupler bar has been retained in a position for ready assembly by the pockets 68 in the end bars 70.

In Figures 9 to 12 is illustrated a slightly different form of the bed, one point of difference being that here the equalizer bars are permanently secured to and under the trundle bed. For convenience, the same or similar reference characters are used for some of the corresponding parts. The upholstery is numbered 4, as in Figure 1. The main mattress 6 is supported on the 70 75 80 85 90 95

main spring fabric 8 which is carried by the main frame 10. The trundle frame 12 carries spring fabric 14 and is mounted on rollers 18. The remainder of the structure however has 5 numerous variations and therefore new reference characters are used, these being in the hundreds.

Rigidly secured to the front legs 120 of the main bed frame, are brackets 122 which may be welded or riveted to the legs. The brackets 122 10 are provided with outstanding headed pins 124. Suspended between the pins 124 is a movable side bar or coupler bar 126 provided with slots 128 for fitting over the pins 124. The dimensions of the pin 124 are such that the side bar 126 15 will not bind thereon. Side bar 126 is provided with an elongated slot 130 in one end thereof. The trundle frame 12 includes a rear side bar 132 which is provided near one end with a slot 134 similar to the elongated slot 130. Secured 20 between the side bar 126 and the side bar 132 are two equalizer or guide bars 136 and 138 pivoted to each other at a central point 140. The guide bar 136 is pivoted at one end to a pin 142 which slides in the slot 134 and at the other 25 end to a pin 144 which is mounted in a suitable hole in the removable side bar 126. The other equalizer bar 138 is pivoted at one end to a pin 146 slidably mounted in the slot 130, and at the other end to a pin 148 mounted in a suitable 30 hole in the side bar 132. As the trundle bed frame is slid in and out, the equalizer bars 136 and 138 insure equal movement of the two ends of the trundle bed and true running of the trundle bed as a whole. It follows that due to 35 the use of these equalizer bars 136 and 138 it is impossible for the trundle bed frame 12 to rub against the legs 20 of the main frame 10.

In order to permit the complete collapse of 40 the equalizer bars 136 and 138, the bar 138 is provided with a stirrup portion 150 which fits around the other bar 136.

When it is desired to separate the trundle bed frame from the main bed frame, it is merely 45 necessary to raise the removable side bar 126 from the pins 122 at both ends, by which operation the two frames become entirely disconnected so that one may be withdrawn from the other. To prevent interference between the side bar 126 and the legs 120, the latter may be cut out, as 50 at 152. The manner of attachment of the side bar 126 to the main frame 10 may be varied in numerous ways. The bracket 122 may obviously be placed farther forward if desired, to make 55 the pins more conveniently located. According to a simplified construction, the pins 124 may be located on the front of the legs 120, as indicated in Figure 12. Although the side bar is an angle iron, its upper face may be cut away as at 154, in order to permit the complete extension of the beds when the side bar is attached 60 to the main frame.

To make the combination bed more easily moved, there may be provided brackets 156 which 65 preferably have upturned ends 158. These brackets are located on the main frame 10, as indicated best in Figures 10 and 11, and are located such that when the main frame 10 is lifted up the rear frame member 160 of the trundle frame 12 will be securely held by the brackets 156 both against relative downward movement and (due to the use of the lugs 158) against 70 accidental withdrawal. The front end of the

trundle frame 12 may be supported by special brackets, or if not, it will be sufficiently supported by the side bar 126.

Although no receptacle for bedding has been shown, such a receptacle could be provided in 5 any manner desired, preferably by providing a box under the trundle frame, as in the structure of Figures 1 to 8.

It is to be understood that many other embodiments of this invention, including some in 10 improved form, will be apparent, and in the course of time more will be devised by those skilled in the art. It is not desired that this invention be limited to the details described, for its scope includes all such forms or improvements 15 as come within the spirit of the following claims, construed as broadly as the prior art will permit.

What is claimed is:

1. A bed comprising a main section and a trundle section, a coupler bar normally secured 20 rigidly to the trundle section but detachable therefrom, equalizer bars connecting said coupler bar and said main section and maintaining the same parallel and relatively centered transversely; said sections being separable by rolling 25 apart when said trundle section is detached from said coupler bar; and end bars on said main section positioned to support said coupler bar.

2. A bed comprising a main section and a trundle section, a coupler bar normally secured 30 rigidly to the trundle section but detachable therefrom, equalizer bars connecting said coupler bar and said main section and maintaining the same parallel and relatively centered transverse- 35 ly; said sections being separable but rolling apart when said trundle section is detached from said coupler bar; and end bars on said main section positioned to support said coupler bar; said end bars having a depressed portion for permitting 40 said coupler bar to drop loose from said trundle section when desired.

3. A bed comprising two relatively telescopic sections both normally supported on the floor, and interengageable members on said two sections positioned to remain out of contact as 45 long as both of said sections are resting on the floor, but so positioned when the sections are telescoped as to engage one another if the upper of said sections is lifted, and to support the lower of said sections from the upper of said sections; one of said sections having a shoulder 50 faced in the direction to oppose withdrawal movements and positioned to engage the other section only when the under section is being supported by the upper section and thereby to prevent the relative movement of said sections from 55 their telescoped position.

4. A bed comprising a main section and a trundle section, a coupler bar normally secured rigidly to the trundle section but readily detachable therefrom, equalizer bars connecting said coupler bar and said main section and maintaining the same parallel and relatively centered transversely, said sections being separable by rolling apart without movement of said main section when said trundle section is detached from said coupler bar, and means on the main section adapted to support the coupler bar directly at each end thereof in a position convenient for 60 coupling when disconnected from said trundle section.

HUGO PERLESZ.
